UNITED STATES PATENT OFFICE.

JOHN D. CARROLL, OF WEST LAFAYETTE, INDIANA, ASSIGNOR TO TURBO ROTARY ENGINE COMPANY, OF EVANSVILLE, INDIANA, A CORPORATION OF INDIANA.

ROCKER FOR PISTON-VANES.

1,354,282.

Specification of Letters Patent. Patented Sept. 28, 1920.

Application filed January 20, 1919. Serial No. 272,022.

To all whom it may concern:

Be it known that I, JOHN D. CARROLL, a subject of the King of Great Britain, residing at West Lafayette, in the county of Tippecanoe and State of Indiana, have invented 5 certain new and useful Improvements in Rockers for Piston-Vanes, of which the following is a specification.

This invention relates to rockers or swivel 0 blocks employed as guides and bearing members for piston vanes or blades in steam and gas engines of the rotary and oscillating type. In rotary engines of the eccentric piston type there are employed within the cylinder a rotating drum eccentric to the cylinder and fast on the engine shaft, and a series of radial vanes or blades turning about a stationary bearing concentric with the cylinder and eccentric to the drum, these vanes 5 or blades extending through the circular wall of the drum and having both a sliding and an oscillating movement relative to the latter. In order to provide steam tight joints where the blades pass through the 25 drum, cylindrical rockers or swivel blocks have heretofore been mounted in the drum and formed with central longitudinal slots through which the flat piston blade passes. The steam expansion space lies between the 30 drum and the stationary cylinder or casing, and considerable difficulty has hitherto been experienced in securing steam tight joints where the piston blades pass through the drum, it being necessary to pack both the 35 joint between the blade and the rocker and the joint between the rocker and its bearing in the drum.

The principal object of the present invention is to provide an improved rocker, and 40 more particularly improved packing devices therefor, by which steam tight joints may be secured, friction and wear may be reduced to a minimum, and the packing shall be self-compensating for wear.

45 With these and other objects in view, which will appear in the following detailed description, the invention consists in the improved structural features hereinafter described in one practical and improved form, 50 and definitely pointed out in the claims hereunto appended.

Referring to the accompanying drawings, wherein I have illustrated an embodiment of

the invention which has been found in practice to yield satisfactory results—

55

Figure 1 is an elevation, broken out between its ends and partly in longitudinal section of my improved rocker or swivel block;

Fig. 2 is a similar view as viewed from the 60 bottom of Fig. 1, and with one of the heads of the rocker in diametric section;

Fig. 3 is a cross section taken on the line 3—3 of Fig. 2;

Fig. 4 is an end elevation as seen from the 65 right of Fig. 2;

Fig. 5 is an enlarged detail in horizontal section on the line 5—5 of Fig. 1.

Figs. 6 and 7 are sectional views, in planes at right angles to each other, through a portion of the engine cylinder, piston drum, driven shaft and bearing boss, illustrating the relation of the rocker to the piston vane 70 and other parts with which it immediately coöperates.

75 Referring to the drawings, 10 designates the circular wall of the cylinder within which is rotatably mounted a drum 11 that is keyed to the driven shaft 12 through a central web portion (not herein shown), the 80 shaft being journaled in stationary bearing bosses 13 integral with the end walls of the cylinder. Mounted at intervals in the cylindrical portion of the drum 11 are rockers or swivel blocks designated as an entirety by 14 that are slotted lengthwise to receive the piston blades or vanes 15, which latter are rotatably mounted on the bearing bosses 13 through the agency of eccentric straps or bearing rings 16. The features 85 90 thus far described are broadly common to engines of the general type referred to, and for a detailed description thereof reference may be had to Letters Patent No. 1,320,531, granted to me on the 4th day of November, 95 1919.

100 Describing now the novel improvements with which the present invention is concerned, these relate to structural features of the rocker or swivel block 14, and more particularly the packing features thereof, and are best shown in Figs. 1 to 5 inclusive. By reference to these views it will be seen that this member, which occupies a circular bearing seat 17 in the cylindrical portion of the 105 drum 11 (Fig. 6) with its ends or heads

journaled in circular bearings 18' (Fig. 7) in the web members of the drum, is, for purposes of assembling with the form of piston vanes herein shown, made in sections. These 5 comprise two main body pieces 18 of segment form in cross section that are spaced apart in parallel relation by segment blocks 19 interposed between their ends, and united by counter-sunk bolts 20. This construction 10 provides a central longitudinal slot 21 through the rocker, through which slot extends the piston vane 15.

In order to provide steam tight joints between the contacting faces of the piston 15 blade and rocker and of the rocker and its bearing 17, each of the segmental body pieces 18 is formed with a longitudinal slot 22, these two slots 22 lying in a plane at right angles to the slot 21 which accommodates the piston vane, as clearly shown in 20 Fig. 3. Within each of the slots 22 are mounted with a snug sliding fit inner and outer metallic packing strips 23 and 24 respectively; and these packing strips are connected to each other at intervals by tie-bolts 25 each of which conveniently consists of male and female screws 25 and 26, the heads of which are counter-sunk in the outer faces of the packing strips 23 and 24, respectively, 30 whereby the spacing apart of the strips can be adjusted as desired and the heads of the bolts constitute stops limiting the extent of outward movement of the strips. Between the two strips are inserted springs that normally 35 push the strips apart, these springs conveniently taking the form of spiral compression springs 27 encircling the tie-bolts. The latter are so adjusted as to length as to permit the two strips to be normally forced 40 slightly beyond the surfaces which they are designated to pack, as clearly shown in Fig. 3.

The side edges of the piston blade are packed against leakage of motive fluid 45 through the agency of short transversely extending packing strips 28 that are seated in sockets 29 in the inner faces of the ends of the rocker, as clearly shown in Figs. 1 and 2, and are normally forced outwardly by 50 springs 30. Preferably, and as herein shown, the inner or bearing edge of each packing strip 28 is formed with a central transverse notch 31 which receives a packing strip on the side edge of the piston blade, 55 such as is shown and described in a co-pending application filed by me concurrently herewith Serial No. 272,021.

The ends of the inner longitudinal packing strips 23 are preferably, and as herein shown, notched at 32 (Fig. 5) to straddle the ends of the transverse packing strip 28.

The circular heads of the rocker are journaled in bearings in the web members of the drum 11, as shown in Fig. 7, and a tight 65 joint of the rocker in these bearings is se-

cured by means of an annular packing on each head consisting, as herein shown, of a split metal ring 33 that is seated in an annular groove or channel 34 formed in the head. The ring 33 normally expands under its own elasticity to a diameter slightly in excess of the diameter of the head, so that its outer surface maintains a steam-tight joint with the circular wall of the bearing, this being enhanced by forming one or more narrow grooves or channels 33' in the outer surface of the ring. This outer surface is furthermore slightly tapered or beveled, as shown in Figs. 1 and 2, to facilitate assembling of the ends of the rocker in their bearings. Each ring is locked against rotation by forming in the inner edge thereof a shallow notch 35 (Fig. 2) that is entered by one end of one of the outer longitudinal packing strips 24.

The above described construction is one which readily lends itself to facility of manufacture and assembling, and in practice has been found to possess the qualities of efficiency and durability in a high degree. 9 The packing strips are self-adjusting to fit any slight irregularity in the surfaces which they engage, and they also automatically take up such wear as occurs from long continued use.

It will be manifest that the benefits and advantages secured by my invention are not dependent wholly upon the employment of all the detail structural features herein shown and described, and that the latter are capable of modification and variation without involving any departure from the principles involved or sacrificing any of the results and advantages secured. Hence I do not limit the invention to the specific details shown and described for purposes of illustration, except to the extent clearly indicated in specific claims.

I claim:

1. A rocker for piston vanes, consisting of a cylindrical body formed with a central longitudinal slot to accommodate a piston vane and with longitudinal slots in the sides of said body in a plane at right angles to said first-named slot, inner and outer packing strips lying in each of said last-named slots, springs between said packing strips forcing them apart, and means for limiting the extent of outward movement of each of said packing strips.

2. A rocker for piston vanes, consisting of a cylindrical body formed with a central longitudinal slot to accommodate a piston vane and with longitudinal slots in the sides of said body in a plane at right angles to said first-named slot, inner and outer packing strips lying in each of said last-named slots, tie-bolts connecting each pair of inner and outer strips at spaced intervals and limiting their extent of outward 130

movement, and springs between said strips forcing them apart.

3. A rocker for piston vanes, consisting of a cylindrical body formed with a central longitudinal slot to accommodate a piston vane and with longitudinal slots in the sides of said body in a plane at right angles to said first-named slot, inner and outer packing strips lying in each of said last-named slots, tie-bolts connecting each pair of inner and outer strips at spaced intervals and limiting their extent of outward movement, the heads of said tie-bolts being countersunk below the bearing surfaces of said strips, and coil-springs encircling said tie-bolts and forcing said strips apart.

4. A rocker for piston vanes, consisting of a cylindrical body formed with a central longitudinal slot to accommodate a piston vane and with solid ends or heads, spring-pressed packing strips in the sides of said body and projecting through the side walls of said longitudinal slot, and other spring-pressed packing strips mounted in the heads of the rocker and projecting through the end walls of said longitudinal slot.

5. A rocker for piston vanes, consisting of a cylindrical body formed with solid ends or heads, a central longitudinal slot to accommodate a piston vane, and longitudinal slots in the sides of said body in a plane at right angles to said first-named slot, inner and outer packing strips lying in each of said last-named slots, springs between and forcing said strips apart, and other spring-pressed packing strips mounted in the heads

of the rocker and projecting through the end walls of said longitudinal slot.

6. A rocker for piston vanes, consisting of a cylindrical body formed with annularly 40 grooved solid ends or heads, a central longitudinal slot to accommodate a piston vane, and longitudinal slots in the sides of said body in a plane at right angles to said first-named slot, inner and outer packing strips 45 lying in each of said last-named slots, springs between and forcing said strips apart, other spring-pressed packing strips mounted in the heads of the rocker and projecting through the end walls of said longitudinal slot, and elastic split packing rings mounted in the annular grooves of said heads.

7. A rocker for piston vanes, consisting of a cylindrical body formed with annularly 55 grooved solid ends or heads, a central longitudinal slot to accommodate a piston vane, and longitudinal slots in the sides of said body in a plane at right angles to said first-named slot, inner and outer packing strips 60 lying in each of said last-named slots, springs between and forcing said strips apart, other spring-pressed packing strips mounted in the heads of the rocker and projecting through the end walls of said longitudinal slot, and elastic split packing rings 65 mounted in the annular grooves of said heads, said packing rings being notched laterally to receive the ends of said outer packing strips whereby said rings are locked 70 against turning.

JOHN D. CARROLL.
